INTERNAL COMBUSTION ENGINE

Herbert C. Edwards, Detroit, Mich., assignor to
 Packard Motor Car Company, Detroit, Mich., a
 corporation of Michigan

Application July 21, 1930, Serial No. 469,473
 Renewed May 18, 1933

20 Claims. (Cl. 123—139)

This invention relates to internal combustion engines and more particularly to engines of the compression-ignition type in which fuel is injected into the combustion chambers through a mechanism actuated by an engine part.

The invention has to do more particularly with the starting of engines in which liquid fuel is injected into compressed air charges at a pressure developed in accordance with the engine speed. With this type of engine, the degree of fuel atomization and the pressure at which the fuel is injected becomes less as the speed of the engine is reduced, and the fuel is not injected into the compressed air in the combustion chambers at a pressure or in an atomized condition conducive to easy starting when the crank shaft is being turned slowly by a source of external power.

An object of the invention is to regulate the timing, the pressure and the atomization of liquid fuel injected into compressed air in the cylinders of a compression-ignition engine in a manner to promote combustion by compression when the engine is being started.

Another object of my invention is to provide an internal combustion engine of the compression-ignition type in which the timing of the fuel injection is manually retarded, and the normal pressure produced against the fuel to be injected is increased beyond that developed by the normal actuating mechanism.

A further object of the invention is to provide a manual control for regulating the actuation of the fuel injection devices of a compression-ignition engine so that during starting, fuel charges will be injected into the combustion spaces when the compressed air charges are at substantially their highest compression, under a pressure such that sufficient penetration occurs to quickly cause a thorough intermingling of the fuel mixture elements.

Still another object of the invention is to provide a manual control which can be actuated during the starting of an engine of the compression-ignition type to bring into effective relation a faster moving fuel pump actuating cam mechanism and at a later time in the compression stroke of the engine operation than the time of the injection under self operating conditions.

These and other objects of the invention will appear from the following description taken in connection with the drawings, which form a part of this specification, and in which:

Fig. 1 is a rear elevational view of a radial engine, partially broken away and partially in

section to show a fuel injecting device and the actuating mechanism;

Fig. 2 is an elevational view showing the fuel injection mechanism actuating cams with the faster cam in effective position;

Fig. 3 is a sectional view of the engine taken on line 3—3 of Fig. 1;

Fig. 4 is a perspective view looking at the front end of the control sleeve;

Fig. 5 is a fragmentary sectional view of one of the fuel injection mechanisms associated with an engine cylinder.

Referring now to the drawings by characters of reference, 10 represents generally the crank case of a compression-ignition type of internal combustion engine from which nine air-cooled cylinders 11 extend radially, the cylinders being secured under compression around the wall of the crank case by compression rings, one of which is indicated at 12. The cylinders are formed with an integral dome 13 and secured upon each of the domes is a head 14. Each of the associated heads and domes is formed with a single Venturi passage 15 leading into the interior of the associated cylinders, such passages serving as both the air inlet and the exhaust outlet for the combustion chamber which is between the cylinder domes and the pistons 16. In order to control the passages 15, there is provided with each a valve 17 which is normally closed by a plurality of springs 18 and opened by conventional engine actuated mechanism including a push rod 19 which extends into the crank case.

A diaphragm, or internal wall 20 is secured within the crank case and is formed with a central opening in which is arranged a bearing 21 for supporting one end of the crank shaft 22, the crank shaft projecting axially through the crank case. Arranged in a relation substantially parallel to the diaphragm is a detachable rear wall 23 which closes the open end of the crank case, and detachably secured to the rear wall is a starting device, indicated generally at 24, which is preferably of the inertia type as illustrated in Patent No. 1,739,469, issued December 10, 1929, to R. P. Lansing. Such starting device is arranged with a manually reciprocable jaw 25 projecting into the crank case in alignment with the rear end of the crank shaft, so that it can be moved into a driving relation therewith.

The engine illustrated is of the compression-ignition, or Diesel type, which operates on a four-stroke cycle, air charges being drawn into the cylinders through the passages 15 upon the suction strokes of the pistons, during which time

the valves 17 are mechanically held open. The valves are next closed and the compression strokes then occur, and during the compression strokes, charges of fuel oil are injected under a high pressure at any engine speed and in an atomized condition into the air charges being compressed, such that the mixture thereof with the compressed air will form a charge of a character producing quick combustion. There is associated with each cylinder a fuel injection device which consists generally of a nozzle portion 26 and a pump portion 27, the nozzle portions being secured rigidly to the cylinders and arranged to project through the walls thereof so that the fuel charges can be injected directly into the interior of the cylinders.

Each nozzle consists of a barrel 28 having a detachable end 29 extending through the associated cylinder wall and formed with a conical outlet opening in which the valve head 30 is arranged. The valve stem 31 is arranged to be moved into engagement with the stop member 32 by a spring 33 and such stop member is adjusted to prevent the valve from entirely closing. The barrel 28 is formed with a downwardly extending neck portion which is provided with a passage 34 leading to the hollow chamber in the barrel through which the valve rod extends. Such nozzle neck is screwed into the casing 35 of the associated pump unit and bears against a ring spacer 36 which maintains the pump barrel 37 in position within the casing 35, there being a pair of spring-pressed valves 38 associated with the ring member and the barrel to prevent liquid fuel returning to the pump structure from the nozzle structure. A plunger 39 is arranged to reciprocate within the pump barrel and a fuel inlet manifold 40 communicates with all of the pumps, there being a union 41 in the manifold structure associated with each of the barrels, and ports 42 extend through the casing and the barrel to establish communication between the fuel feeding manifold and the interior of the barrel. Such ports are controlled by the position of the plunger so that when a plunger uncovers the ports 42, liquid fuel is moved into the pump barrel and nozzle completely filling the chambered portions therein. The pump plungers are moved in their injection strokes by an adjustable mechanism, which will be hereinafter described, and during such movement they close the ports 42, their stroke after closing such ports determining the quantity of fuel which is displaced from the nozzle into the cylinders.

It will be seen that the speed of the plunger movement determines the degree of pressure under which the fuel charge is forced past the nozzle valve. The effective stroke of the plungers will force fuel past the valves 31 and from the nozzles in a manner such that the fuel charges are directed into the cylinders in a conical spray. The air inlet passages are formed and arranged so that they cause rotation of the air in the cylinders and such rotation continues during the following compression stroke of the piston, the fuel charges being sprayed into such compressed rotating air charges.

The degree of fuel atomization and the extent of the pressure at which it is injected determines the degree of the intermingling of the oil with the air and, therefore, it is necessary that there be sufficient atomized fuel penetration of the air to cause a uniform distribution if efficient engine operation is to result. It is also necessary that the atomization and penetration of the air by

the fuel oil be of a certain character if combustion is to be attained when the cylinders are cold, as they are when starting. With the type of injection mechanism described, in which the pressure behind the fuel varies in accordance with the crank shaft speed, difficulty is experienced when turning the crank shaft at a slow speed in starting the engine to produce a sufficient pressure behind the fuel charges, because of the consequent slow movement of the fuel pumps, which is not sufficient to cause the atomization and penetration of the compressed air charges to produce a mixture which will support combustion.

This invention has to do particularly with mechanism for injecting fuel oil in an atomized condition and at a sufficient pressure to cause an intermingling with the compressed air in the cylinders such that ignition will readily result from compression when the crank shaft is being slowly turned through the application of a starting device. To this end, I utilize the regular fuel injecting mechanism for the normal running operation of the engine and provide an auxiliary actuating mechanism therefor which is effective only during the application of the starting mechanism to the crank shaft. This auxiliary actuating mechanism is made effective manually and is placed in ineffective relation when the starting device is released from the crank shaft. In carrying out such invention, I propose that the liquid fuel charges will be injected, during the turning of the crank shaft by the starting device, at a pressure which will cause the fuel to penetrate substantially to the center of the cylinder and in a finely atomized condition so that one rotation of the compressed air in the cylinder will cause a uniform distribution therein of the atomized liquid fuel.

Under normal running operation, crank shaft actuated mechanism is provided for causing the pump plungers to move in their injection strokes, and such mechanism is returned to a position uncovering the ports 42 by means of the coil spring 43. A fuel plunger push rod 44 extends through the crank case and has associated therewith a rod 45 which is pivotally connected with a link 46 carried by a regulating ring 47 rotatably mounted within the crank case. The ring 47 can be actuated through the association of a tooth segment 48 with a rack 49 which is fixed to the ring, the segment being rotated by means of the shaft 50 which is in turn actuated through suitable mechanism connected with the lever 51. Associated with each of the levers 45 is a slipper or rock lever, as shown at 52, 53 and 54, each being carried by a shaft 55 supported by the diaphragm and the rear casing cover 23. The free ends of the rock levers are formed with a curved groove in which the associated lever 45 is adjustably positioned by means of the ring 47 and the connecting links 46, so that upon movement of the levers 44, lengthwise of the slippers, the effective stroke of the pump plungers can be simultaneously varied.

Arranged interiorly of the pivoted slippers 53, for actuating the same to cause an injection stroke of the pump plungers, is a cam 56 which is provided with four lobes 57, 58, 59 and 60. A cam 60' is formed with an internal ring gear 61 with which the gear 62 meshes, and this gear is mounted integrally on the same shaft with the gear 63 which is arranged adjacent the end wall of the casing. Meshing with the gear 63 is a gear and clutch member 64 which is keyed to

the rear end of the crank shaft, a pin 65 being screwed into the crank shaft to secure the member axially. This arrangement of gearing, just described, is related so that rotation of the crank 5 shaft will cause rotation of the cam 56 in a direction opposite to that of the crank shaft and at one-eighth the speed of rotation thereof. The rotation of the cam 56 is such that upon each two revolutions of the crank shaft, the lobes 57, 10 58, 59 and 60 will cause one actuation of each of the nine slippers associated with the fuel injection mechanisms. The cam 60' is also provided with a series of four lobes 72, one of which is shown in Fig. 1, for actuating slippers 73, mounted 15 on the shafts 55, with which the valve push rods 19 are associated so that during the suction and exhaust strokes of the pistons, the valves are held open thereby.

As before stated, I have found that with the 20 fuel injection mechanism described, sufficient penetration of the compressed air charges in the cylinders and a desirable atomization of the fuel is attained during engine running operation under load to result in combustion by compression, 25 but when the crank shaft is being turned slowly by an auxiliary source of power, such as a starting device, the rotation is so slow that the resulting action upon the fuel injection mechanism will not cause sufficient pressure to be exerted 30 against the fuel charges to result in the required penetration of the air charges or sufficient atomization to support combustion. In order to secure this necessary pressure and atomization, and to inject the fuel at a time during the air 35 compression when the best efficiency will result, I provide an auxiliary mechanism for actuating the slippers associated with each of the injection devices. To this end I provide each of the fuel mechanism slippers with an extended portion 40 74 so that they can also be actuated by a single lobe cam 75 which is fixed to be driven with and at crank shaft speed. This cam, running at crank shaft speed, will move eight times as fast as the regular fuel actuating cam 56 and, consequently, 45 will cause a much faster stroke of the pump plungers than would be caused by the cam 54, thus resulting in a highly increased pressure and an atomization beyond that which would be attained with the cam 56 in effective position 50 when the crank shaft is turning at slow speeds.

In addition, the cam 75 is arranged to cause an injection stroke of the plungers at a later time in the air compression stroke than that which is caused by the cam 56. The cam 75 is 55 preferably arranged to cause fuel injections just shortly before the pistons reach the top of their compression strokes, while the cam 56 is preferably arranged during engine operation so that the fuel injections occur in a range between 40 60 to 20 degrees before the pistons reach top center in the compression stroke. I have found that when starting, this delay in timing and the provision of pressure behind the fuel charges to cause a substantial penetration of the compressed air charges in a well atomized condition, materially assists in the quick starting of engines of the compression-ignition type operating on liquid fuel of low volatility, and as a result, very little turning of the crank shaft is required to 65 cause combustion by compression.

Manually controlled mechanism is associated 70 with the cams 56 and 60' for regulating the position of the cam 56 angularly relative to the crank shaft so that either the cam 56 or 75 will be effective. The cam 75 is formed with an

extended hub portion 76 the rear end of which is keyed to the crank shaft as indicated at 77, the hub 78 of the cam 56 telescopes the hub 76, while the hub of the cam 60' telescopes the hub 78 of the cam 56. Keyed upon the rear end of the hub 78 is a driving sleeve 79 which is provided with two peripheral rows of teeth 66 and 67, a retaining nut 80 being screwed upon the rear end of the crank shaft and engaging the hub 78 and the driving sleeve 79 to secure them in desired axial position. The hub 81 of the cam 60' is provided at its rear with peripheral teeth 82 with which teeth 68 on the axially movable clutch member 83 are arranged to mesh. The clutch member 83 is circular in form and a yoke 84 is associated therewith to move the same axially relative to the crank shaft. In order to manually effect movement of the yoke, there is a rod 85 extending therefrom through the rear wall of the crank case, and suitable mechanism can be associated with the rod for operating the same from a remote point. The yoke is normally pressed forwardly by a coil spring 86 which bears against the rear crank case cover. The clutch member 83 is also provided with teeth 87 which can be moved to mesh between either of the rows of teeth 66 or 67 on the driving sleeve 79.

The teeth 66 and 67 on the driving member are arranged in different angular relation relative 105 to the crank shaft so that the teeth 87 on the clutch member meshing with either row of teeth will cause the cam 56 to rotate in two different angular relations relative to the crank shaft and the cam 60'. In other words, when the teeth 87 110 mesh with one or the other of the rows of teeth on the driving sleeve, the cam 56 will be in an advanced or in a retarded angular relation relative to the crank shaft. Such two angular relations will cause the lobes of the cam 56 to actuate 115 the rock levers or slippers in advance of the single lobe on the cam 75 or in a range extending between 40 and 20 degrees before the pistons reach their top compression stroke, but when the cam 56 is retarded then the lobes thereon are in a 120 position such that they would actuate the slippers approximately when the pistons have reached the top of their compression stroke. When the cam 56 is in advanced angular position relative to the crank shaft, the lobes 57, 58, 59 125 and 60 will actuate the slippers and are of such length that they will maintain the slippers in raised position during the times that the single lobe of the cam 75 passes thereunder thus masking the cam 75 causing it to be ineffective. When 130 the cam 56 is shifted to its position where the lobes are effective, at top stroke of the piston, the lobe of the cam 75 will engage the slippers in advance of the lobes 57, 58, 59 and 60 and will maintain the slippers in raised position at the times at which 135 the lobes 57, 58, 59 and 60 will pass thereunder, thus making the cam 56 ineffective. This latter relation is caused by moving the clutch member 84 rearwardly so that the teeth 87 mesh with the teeth 66 of the driving member and this relation is desirable when starting the engine because at such time the slow turning of the crank shaft will cause a slow movement of the cam 56 and the resulting movement imparted to the pump plungers thereby is too slow to cause proper penetration of the compressed air charges by the fuel charges to result in proper mixture to cause combustion and with the cam 75 effective, which is running eight times as fast as the cam 56, the movement imparted to the plungers 140

will be much increased and, therefore, the pressure imparted to the fuel injected into the cylinder will be much higher and sufficient to cause the fuel charges to materially penetrate the compressed air charges so that a homogenous mixture will result. In starting the engine, the rod 85 is pulled rearwardly by the operator, causing the teeth 87 to mesh with the teeth 66, and is held in such position while the jaw 25 of the 5 starter is applied to the clutch portion of the gear member 64. After several revolutions of the crank shaft through the application of the starter, the engine will become self-ignited and the rod 85 can then be released so that the clutch 10 84 is moved forwardly by the spring 86 causing the teeth 87 to disengage with the teeth 66 and to move into engagement with the teeth 67 on the driving member, thus making the cam 75 ineffective and making the cam 56 effective.

15 It will be observed that every third one of the teeth 66 and 67 is longer circumferentially than the teeth intermediate the same, while every third space between the teeth 87 on the clutch is longer circumferentially than the spaces between the other teeth. The longer teeth of the sleeve and the longer recesses of the clutch are complementary, hence there are only four positions in which the clutch can be meshed in driving relation with each of the two rows of teeth on the driving 20 sleeve. The clutch 83 is in constant mesh with the teeth 82 on cam 60' which is always in relation to be driven by rotation of the crank shaft, and the teeth 66 on the clutch are staggered with respect to the teeth 67 so that they are slightly 25 in advance thereof in the direction of the rotation of the sleeve. Normally the spring 86 holds the clutch 83 in a forward position wherein the teeth 87 mesh with the row of teeth 67 on the sleeve. In starting the engine, the clutch must 30 therefore be shifted from the teeth 67 into engagement with the teeth 66, and this can be accomplished upon shifting of the clutch from the teeth 67 and permitting it to rotate a sufficient degree in advance of the teeth 67 to mesh with 35 the complementary teeth 66, this being in a clockwise direction looking at the front of the engine. During this rotation, the clutch moves only at one-eighth crank shaft speed and consequently 40 the change in the angular relation of the cam 56 will be eight times the degree of rotation of the clutch, the teeth 66 and 67 being staggered relatively so that the clutch 83 will be retarded approximately 40 degrees on the crank shaft angle 45 before being engageable. After the engine has started and it is desired to shift the clutch out of engagement with the teeth 66 and back into engagement with the teeth 67, so that the cam 56 will be effective, then upon disengagement 50 from the teeth 66 the clutch must be allowed to be driven nearly a quarter revolution, that is a 55 quarter revolution minus the difference in the angle between the complementary teeth 66 and 67, before it can be meshed with the teeth 67. As the crank shaft is turning eight times as fast 60 as the clutch during this rotation in the shifting operation, then the crank shaft will have made nearly two revolutions during the rotation of the clutch so that it will have rotated 720 degrees less eight times the angle of the staggered relation 65 between the complementary teeth 66 and 67 and consequently the cam 56 will be clutched with the sleeve so that its lobes will be effective to operate the fuel injection devices approximately 40 degrees before the pistons reach top center. During this shifting operation, the mo-

mentum which the crank shaft has gained in starting will continue for a sufficient time, even though the starter is disconnected, so that the slight delay in driving the cam 56 after shifting the clutch from starting relation is not of serious consequence in a self-ignition engine because the temperature of the cylinders has been raised and the engine will become self-ignited before effective momentum of the crank shaft ceases. With the four circumferential relations in which the clutch can mesh with the sleeve to drive the cam 56, the cam timing for actuating the plunger push rods will not be disturbed in any possible position of adjustment as the sleeve is keyed to the cam and the four lobes on the cam are in a definite relation with the meshing positions of the sleeve.

It will be seen that the cam 56 is driven from the gear 64 keyed to the crank shaft through means of the gears 63 and 62, the cam 60', the clutch member 83, and the driving sleeve 79 so that by shifting the clutch 84 the cam 56 can be advanced or retarded in an angular relation relative to the crank shaft. In starting, when the cam 75 is effective to cause the injection strokes of the pump plungers the time at which the fuel is injected is just before the pistons reach top center on the air compression strokes, thereby resulting in efficient engine operation. The speed of the cam 75 when the starter is applied is sufficient to cause a pressure against the fuel charges which are injected into the cylinders such that they will be projected substantially to the axis of the rotating compressed air charges and in this manner, there will be a homogenous mixture prepared which results in quick combustion even though the crank shaft is turning at a slow speed.

While I have herein described in some detail a specific embodiment of my invention, which I deem to be new and advantageous and may specifically claim, I do not desire it to be understood that my invention is limited to the exact details of the construction, as it will be apparent that changes may be made therein without departing from the spirit or scope of my invention.

What is claimed is:

1. In a compression-ignition engine, a pressure injection device for introducing liquid fuel into compressed air charges in the engine, normally effective mechanism operated by the engine for actuating the injection device, a second mechanism for actuating the injection device at a faster speed and a later time than the normally effective mechanism, and manually operable means for maintaining the normally effective mechanism in ineffective relation, said mechanisms being effective only one at a time to actuate the injection device.

2. In a compression-ignition engine, devices for injecting liquid fuel under pressure into compressed air charges in the engine cylinders, mechanism driven at a reduced speed from the engine for actuating said devices, another mechanism driven at a faster speed than the other mechanism and effective at a later time for actuating the devices, only one of said mechanisms being effective at a time, and manually actuated means for moving the slower mechanism into ineffective position when the engine is being cranked.

3. In a compression-ignition engine, pressure injection devices for introducing liquid fuel into compressed air charges in the engine, a pair of independently driven cams for actuating said devices, one of said cams being driven at a faster

- speed and effective at a later time than the other, and manually actuated means for changing the relative angular relation of the cams to cause one or the other to be effective.
5. In a compression-ignition engine, pressure injection devices for introducing liquid fuel into compressed air charges in the engine to form explosive mixtures, a pair of cams rotated at different speeds for actuating the injection devices, said faster cam being effective at a later time than the slower cam and normally ineffective, and manually operable means for shifting the slower cam into an ineffective position while cranking the engine, said mechanisms being effective one at a time to actuate the injection devices. 80
10. In a compression-ignition engine, a pressure injection device for introducing liquid fuel into the compressed air charges in the engine, a crank shaft, a single lobe cam fixed to the crank shaft for actuating the fuel injection device, a cam rotatably associated with the crank shaft for actuating the fuel injection device, said cams being effective only one at a time, an air valve actuating cam, reduction gearing intermediate the crank shaft and the air valve cam, a driving connection between the air valve cam and the cam rotatably associated with the crank shaft, said driving connection normally maintaining the slow speed cam in effective position relative to the fuel injection device and in a relation shielding it from actuation by the fast cam, and manually operable means for shifting the driving connection to place the slow speed cam in an ineffective position in which lobes thereon are shielded from actuating the fuel injection device by the faster cam. 85
15. In a compression-ignition engine, pressure injection devices for introducing liquid fuel into compressed air charges in the engine to form explosive mixtures, a crank shaft, a pair of cams for actuating the injection devices, one of said cams being fixed to the crank shaft and the other cam being driven at a reduced speed from the crank shaft, and manually controllable means for regulating the position of the slower cam angularly relative to the crank shaft to place it in a relation with the other cam so that it is in ineffective relation with the injection devices. 90
20. In a compression-ignition engine, a pressure injection device for introducing atomized liquid fuel into compressed air charges in the engine, a crank shaft, a cam for actuating the fuel injection device when starting the engine, said cam being fixed to the crank shaft, another cam for actuating the fuel injection device during running operation, said cam being rotatably associated with the crank shaft, an air valve actuating cam, reduction gearing intermediate the air valve actuating cam and the crank shaft, a driving sleeve fixed to the normal operation cam, and a clutch member intermediate the driving sleeve and the air valve actuating cam for causing rotation of the normally effective cam with the air valve cam, said clutch member being engageable in two relations with the driving sleeve 100 to change the angular position of the slower speed cam to place it in effective or ineffective position, said clutch member being manually shiftable to establish a connection placing the slow speed fuel cam in ineffective position. 105
25. In a compression-ignition engine, a pressure injection device for introducing atomized liquid fuel into compressed air charges in the engine, normally effective mechanism including a driving sleeve operated by a moving part of the engine for actuating the injection device, a second mechanism for actuating the injection device at a faster speed and at a later time than the first mentioned mechanism when effective, only one of said mechanisms being effective at a time, a manually operable means cooperating with said driving sleeve for shifting the normally effective mechanism into ineffective relation. 110
30. In a compression-ignition engine, a pressure injection device for introducing atomized liquid fuel into the compressed air charges in the engine, a crank shaft, a cam fixed to the crank shaft, another cam adapted to be driven at a reduced speed from the crank shaft, reduction gearing including a driving sleeve having two sets of teeth arranged in different angular relation and a shiftable member for effecting driving through either set of teeth, and means for normally maintaining the shiftable member in engagement with the set of teeth causing the slower speed cam to be effective. 115
35. In a compression-ignition engine, a pressure injection device for introducing liquid fuel into the compressed air charges in the engine, a crank shaft, a cam for actuating the fuel injection device fixed to the crank shaft, a normally effective cam for actuating the fuel injection device, said normally effective cam being rotatably associated with the crank shaft, an air valve actuating cam, reduction gearing intermediate the crank shaft and the air valve actuating cam, a driving connection intermediate the air valve actuating cam and the cam rotatably associated with the crank shaft, said driving connection being shiftable to change the angular relation of the associated cam relative to the crank shaft to 120 place it in effective or ineffective position, manually operable means for moving the driving connection into a relation causing the slow speed cam to be ineffective, and means for automatically maintaining the driving connection in a relation 125 maintaining the slower cam in effective position, said cams being effective one at a time and the effective cam masking the injection device from the other cam. 130
40. In a compression-ignition engine, a pressure injection device introducing liquid fuel into compressed air charges in the engine, a crank shaft, a cam for actuating the fuel injection device rotatably associated with the crank shaft, an air valve actuating cam, reduction gearing intermediate said crank shaft and said air valve cam, and a driving connection between the air valve cam and the cam for actuating the fuel injection device, said driving connection be- 135
45. In a compression-ignition engine, a pressure injection device for introducing liquid fuel into compressed air charges in the engine, a crank shaft, a cam for actuating the fuel injection device fixed to the crank shaft, a normally effective cam for actuating the fuel injection device, said normally effective cam being rotatably associated with the crank shaft, an air valve actuating cam, reduction gearing intermediate the crank shaft and the air valve actuating cam, a driving connection intermediate the air valve actuating cam and the cam rotatably associated with the crank shaft, said driving connection being shiftable to change the angular relation of the associated cam relative to the crank shaft to 140 place it in effective or ineffective position, manually operable means for moving the driving connection into a relation causing the slow speed cam to be ineffective, and means for automatically maintaining the driving connection in a relation maintaining the slower cam in effective position, said cams being effective one at a time and the effective cam masking the injection device from the other cam. 145
50. In a compression-ignition engine, a pressure injection device for introducing liquid fuel into compressed air charges in the engine, a crank shaft, a cam for actuating the fuel injection device fixed to the crank shaft, a normally effective cam for actuating the fuel injection device, said normally effective cam being rotatably associated with the crank shaft, an air valve actuating cam, reduction gearing intermediate the crank shaft and the air valve actuating cam, a driving connection intermediate the air valve actuating cam and the cam rotatably associated with the crank shaft, said driving connection being shiftable to change the angular relation of the associated cam relative to the crank shaft to 150 place it in effective or ineffective position, manually operable means for moving the driving connection into a relation causing the slow speed cam to be ineffective, and means for automatically maintaining the driving connection in a relation maintaining the slower cam in effective position, said cams being effective one at a time and the effective cam masking the injection device from the other cam. 155

- 5 said normally effective cam being rotatably associated with the crank shaft, an air valve actuating cam, reduction gearing intermediate the crank shaft and the air valve actuating cam, a driving connection intermediate the air valve actuating cam and the cam rotatably associated with the crank shaft, said driving connection being shiftable to change the angular relation of the associated cam relative to the crank shaft to place 10 it in effective or ineffective position, manually operable means for moving the driving connection into a relation causing the slow speed cam to be ineffective, and a coil spring for automatically maintaining the driving connection in a 15 relation maintaining the slower cam in effective position, said cams being effective one at a time and the effective cam shielding the injection device from actuation by the other cam.
14. In a radial compression-ignition engine, 20 pressure injection devices for introducing liquid fuel into compressed air charges in the cylinders, a crank shaft extending axially of said devices, a cam fixed to the crank shaft for causing injections of said devices, a second cam rotatably associated with the crank shaft for actuating said devices at a slower speed than the fixed cam, mechanism for driving said slower speed cam from the crank shaft, said cams being effective 25 one at a time and provided with lobes of a character such that the effective cam will mask the ineffective cam from the injection device, manual operable means associated with the driving connection of the slow speed cam for moving it angularly relative to the crank shaft into ineffective 30 position during cranking of the engine for starting, and means for normally maintaining the driving mechanism in a relation causing the slow speed cam to be effective.
15. In a compression-ignition engine, a pressure 35 injection device for introducing liquid fuel into the compressed air charges in the engine, a crank shaft, a single lobe cam having a hub extending axially of and fixed to the crank shaft, a slow speed cam rotatably mounted upon the 40 extended hub of the cam, fixed to the crank shaft, an air valve actuating cam mounted upon the hub of the slow speed cam, a reduction driving connection between the crank shaft and the air valve actuating cam, a driving connection between the air valve cam and the slow speed cam, and a retainer for securing the slow speed cam and the air valve cam axially on the hub of the 45 cam fixed to the crank shaft.
16. In a compression-ignition engine, a pressure injection device for introducing liquid fuel into compressed air charges in the engine, a crank shaft, a cam fixed to the crank shaft for actuating the fuel injection device, a starting jaw fixed to the crank shaft, an air valve actuating cam, reduction gearing intermediate the starting jaw and the air valve actuating cam, a second cam for actuating the fuel injection device, a driving connection between the air valve actuating cam and the second cam, and means for shifting the driving connection to place the second cam in effective or ineffective relation, 50 said cams being effective one at a time and the effective cam shielding the injection device from actuation by the other cam. 80
17. In an internal combustion engine, a pressure device for injecting liquid fuel into compressed charges of air in the engine, a pair of cams effective one at a time for actuating said injection device, said cams being driven by the engine at different speeds relatively, and manually adjustable means for placing either cam in effective actuating relation with the injection device. 85
18. In an internal combustion engine, a pressure device for injecting liquid fuel in the compressed charges of air in the engine, a pair of engine driven cams effective one at a time for actuating said injection device, said cams being timed differently in the compression cycle, and manually adjustable means for placing either cam in effective actuating relation with the injection device. 90
19. In an internal combustion engine, a pressure device for injecting liquid fuel into compressed charges of air in the engine, a pair of cams effective one at a time for actuating said injection device, said cams being driven at different speeds relatively and timed differently, and manually adjustable means for placing either cam in effective actuating relation. 95
20. In an internal combustion engine, a pressure device for injecting liquid fuel into compressed charges of air in the engine, a pair of cams effective one at a time for actuating said injection device, said cams being driven at different speeds relatively and timed differently, and means manually maintained in one position to place one of the cams in ineffective relation with the injection device. 100
